[57] **ABSTRACT**

Paraffinic hydrocarbons are converted to other hydrocarbons by contacting with a catalyst comprising trifluoromethanesulfonic acid. In another embodiment, normal paraffins are isomerized with high selectivity to skeletal isomers containing the same number of carbon atoms by contacting same with a catalyst comprising trifluoromethanesulfonic acid and a Group Vb metal fluoride.

3 Claims, No Drawings

ISOMERIZATION OF PARAFFINIC
HYDROCARBONS WITH
TRIFLUOROMETHANESULFONIC ACID

This invention relates to hydrocarbon conversion. In accordance with another aspect, paraffinic hydrocarbons are converted to other hydrocarbons by contacting the paraffinic hydrocarbons with a catalyst comprising trifluoromethanesulfonic acid. In accordance with another aspect, paraffinic hydrocarbons are isomerized by contacting the paraffinic hydrocarbons with a catalyst comprising trifluoromethanesulfonic acid and a Group Vb metal fluoride. In accordance with a further aspect, normal paraffins are isomerized with high selectivity to skeletal isomers containing the same number of carbon atoms by contacting the paraffins with a catalyst comprising trifluoromethanesulfonic acid and a Group Vb metal fluoride.

It is well known that the more highly branched isomers of the paraffinic hydrocarbons occurring in petroleum gasoline fractions are more valuable than the corresponding slightly branched or straight chain hydrocarbons because of their higher octane ratings. The demand for motor fuels of greater octane number has increased markedly as the automotive industry has provided gasoline engines with increasingly higher compression ratios to attain greater efficiency. One of the economically important ways in which the increased demands for high octane fuels can be met is through the isomerization of the light naphtha components of such fuels.

It may be generally stated that the isoparaffinic and branched chain paraffin hydrocarbons are of greater commercial value to the petroleum industry than the corresponding straight chain hydrocarbons. Thus, for example, 2,2-dimethylbutane has a higher octane rating than the isomeric normal hexane. Isobutane is more valuable than normal butane since the former can be used as a basis for the preparation of 8-carbon-atom, branched chain hydrocarbons by alkylation with butylene.

The isomerization of normal paraffin hydrocarbons into the corresponding branched chain homologs is well known. For effecting the isomerization, it is customary to employ certain metal halides, particularly aluminum chloride or aluminum bromide, in conjunction with certain promoters such as hydrogen chloride, hydrogen bromide, or boron fluoride. Recently, strong acid systems such as solutions of fluorosulfonic acid and antimony pentafluoride have also been disclosed as useful isomerization catalysts. An important problem arising with the use of these highly active catalysts is that they promote side reactions such as cracking and disproportionation. These side reactions are particularly evident at high conversion conditions and lead to the formation of substantial amounts of undesirable light and/or heavy side products.

Accordingly, an object of this invention is to provide an improved hydrocarbon conversion process.

Another object of this invention is to provide an isomerization process whereby high selectivity to skeletal isomers is achieved.

Another object of this invention is to provide an improved isomerization process for the conversion of paraffinic hydrocarbons.

A further object of this invention is to provide an improved catalyst for hydrocarbon conversion and isomerization.

Other objects and aspects as well as the several advantages of the invention will be apparent to those skilled in the art upon further consideration of the specification and the appended claims.

In accordance with the invention, a process for the conversion of paraffinic hydrocarbons to other hydrocarbons is provided which comprises contacting the hydrocarbons with a catalyst comprising trifluoromethanesulfonic acid. It has been found that trifluoromethanesulfonic acid alone effects the isomerization and cracking of paraffinic hydrocarbons such as normal hexane.

Further in accordance with the invention, it has been found that normal paraffins can be isomerized with high selectivity to branched isomers containing the same number of carbon atoms by contacting the hydrocarbons with a catalyst comprising trifluoromethanesulfonic acid and a Group Vb metal fluoride.

In accordance with one specific embodiment, n-hexane isomerizes to predominantly neohexane in the presence of a catalyst comprising trifluoromethanesulfonic acid and at least one of phosphorus pentafluoride, antimony pentafluoride and arsenic pentafluoride.

Trifluoromethanesulfonic acid has various advantages not possessed by known superacid catalyst systems including (1) it has a much higher boiling point, hence less is lost on recycle in continuous operation; (2) it does not attack glass so sight gages, etc. made of glass can be used; and (3) it is the strongest protonic acid known and hence smaller amounts of acid are effective.

The catalyst composition of the present invention comprises trifluoromethanesulfonic acid alone or trifluoromethanesulfonic acid with a metal fluoride of a Group Vb element. Specific examples of these metal fluorides include antimony pentafluoride, arsenic pentafluoride and phosphorus pentafluoride, as well as mixtures thereof.

Suitable feeds for the purposes of the present invention comprise normal and branched chain paraffinic hydrocarbons having from four to seven, inclusive, carbon atoms per molecule, and may be exemplified by normal butane, normal pentane, normal hexane, 2-methylhexane, 3-methylhexane, and mixtures thereof. While the feed can substantially comprise the purified paraffinic hydrocarbon stream, it is also contemplated that mixtures of various paraffinic hydrocarbons can be employed.

The reaction conditions for isomerization of the feed can be in the range of 0° to 100° C, usually 15° to 80° C, and pressures sufficient to maintain the hydrocarbon reactants and catalysts as liquid in the reaction zone, and the temperatures and pressures should be chosen accordingly. The time of contact is subject to wide variation, the length of residence time dependent in part upon the temperature and catalyst concentration employed. In general, reaction times ranging from about 5 minutes to 48 hours, preferably 15 minutes to about 2 hours, are employed.

The mole ratio of paraffinic hydrocarbon to Group Vb metal fluoride forming the catalyst of the invention will generally be in the range 50:1 to 0.2:1, preferably 1:1 to 20:1. The mole ratio of trifluoromethanesulfonic acid to Group Vb metal fluoride catalyst will generally

be in the range 100:1 to 0.2:1, preferably 1:1 to 20:1. The mole ratio of trifluoromethanesulfonic acid to paraffinic hydrocarbon when trifluoromethanesulfonic acid alone is used as the catalyst will generally be in the range 0.1:1 to 50:1, preferably 0.5:1 to 20:1.

The process of the invention is conducted as a batch or a continuous operation. The apparatus employed can be of a conventional nature and can comprise a single reactor equipped with sufficient stirring devices. Good agitation is important because the less dense paraffinic hydrocarbon layer is not miscible with the denser liquid acid phase. Unreacted reactants, catalyst and other products of the reaction can be separated from the desired product and from one another such as by distillation and returned in whole or in part to the isomerization zone. The resultant product can be further processed as by alkylation and the like or be employed directly as a high octane gasoline blending agent. The reaction zone is preferably constructed of

10

into a polyethylene separatory funnel. The upper hydrocarbon layer was drained under nitrogen into a Fischer-Porter Aerosol compatibility bottle containing about five grams of potassium carbonate and cooled in a dry ice-acetone bath. The bottle was quickly capped with a head bearing a pressure gage and a silicone septum for withdrawing samples for glc analyses. Results are reported in terms of selectivities based on the glc analyses.

EXAMPLE I

Trifluoromethanesulfonic acid was used alone as the catalyst to effect the isomerization and cracking of n-hexane in accordance with the procedure set forth above. The isomerization was effected at a temperature of 25°C for two hours. In both runs 25 ml (42.5 g, 0.28 mole) of trifluoromethanesulfonic acid and 17.2 g (0.2 mole) n-hexane were used. The results of the normal hexane isomerization are given below in Table I.

TABLE I

Run	Hexane Conv.,%	Selectivity to Cracked Products	Light Products (C ₃ , C ₄ 'S, C ₅ 's)	Heavies	2,2-DMB	DIP+2-MP	3-MP
1	56.0	75.9	60.6	15.3	4.0	15.4	4.7
2	86.1	78.2	61.4	16.8	7.0	11.5	3.5

materials which are resistant to corrosion by the catalyst. For example, the reactor can be a Monel lined reactor. It is preferred that the reaction be carried out under anhydrous conditions in an inert gas atmosphere. Trifluoromethanesulfonic acid fumes copiously upon exposure to air and the Group Vb metal halides are also hydrolyzed on exposure to atmospheric moisture.

30

SPECIFIC EXAMPLES

Paraffinic hydrocarbons were isomerized to isoparaffins with liquid phase catalyst systems of the invention

35

40

EXAMPLE II

Normal hexane was isomerized to its branched isomers by contacting with a mixture of antimony pentfluoride (SbF₅) and trifluoromethanesulfonic acid. In runs 3 and 4, 50 ml (85 g, 0.56 mole) trifluoromethanesulfonic acid and 17.2 g (0.2 mole) n-hexane were used. In runs 3 and 4, 6.6 and 12.3 grams of antimony pentfluoride were used, respectively.

The results of the normal hexane isomerization are given below in Table II.

TABLE II

Run	Hexane Conv.,%	Selectivity to Cracked Products*	**Products			Heavies
			2,2-DMB	DIP+2-MP		
3	95.2	3.6	55.1	31.4	9.9	1.2
4	95.5	3.1	56.8	30.8	9.3	0.6

*Cracked products include propane, butanes, and pentanes.

**2,2-DMB is 2,2-dimethylbutane (neohexane).

DIP is 2,3-dimethylbutane (diisopropyl).

2-MP and 3-MP represent 2-methylpentane and 3-methylpentane, respectively.

utilizing a Monel reactor. The procedure for carrying out the isomerization in a Monel reactor is set forth below.

55

The process runs were carried out in a 300 ml Monel reactor. The trifluoromethanesulfonic acid was charged under nitrogen to the reactor and cooled therein to approximately -40°C. In Examples II, III and IV hereinbelow the Group Vb metal halide was then added to the cold trifluoromethanesulfonic acid until the desired weight was obtained, followed by addition of the paraffin. The reactor was then capped and placed in a thermostated Eberbach reciprocating shaker for any desirable time at a specified temperature.

60

Workup involved cooling the Monel reactor in dry ice-acetone and then rapidly pouring the cold mixture

It can be seen from the above tabulated data that antimony pentfluoride and trifluoromethanesulfonic acid in the liquid phase effect hexane isomerization in 95 percent conversion to branched C₆ isomers with only three percent selectivity to cracked (C₃, C₄'s and C₅'s) products. Neohexane formed in approximately the thermodynamic equilibrium quantity of 55 percent.

EXAMPLE III

Normal hexane was isomerized to its branched isomers by contacting with a mixture of trifluoromethanesulfonic acid and phosphorus pentfluoride at 25°C for 2 hours. In the run 12.6 grams (0.1 mole) of phosphorus pentfluoride, 50 ml (85 g, 0.56 mole) trifluoromethanesulfonic acid, and 17.2 g (0.2 mole) of n-hexane were used. Results of the isomerization of n-hexane are given below in Table III.

TABLE III

Run	Mole Ratio n-C ₆ /PF ₅	n-C ₆ % Conv.	Selectivities*								
			C ₃	i-C ₄	n-C ₄	i-C ₅	n-C ₅	2,2-DMB	DIP & 2-MP	3-MP	Heavies
5	2.0	1.9	2.4	1.1	0.2	1.5	0.1	53.7	31.5	9.7	0

*2,2-DMB represents 2,2-dimethylbutane, DIP represents diisopropyl (2,3-dimethylbutane), 2-MP represents 2-methylpentane, and 3-MP represents 2-MP-3-methylpentane.

It will be noted from the above table that trifluoromethanesulfonic acid in admixture with phosphorus pentafluoride effected hexane isomerization in approximately 95 percent selectivity to branched C₆ isomers with a n-hexane conversion of 1.9 percent.

EXAMPLE IV

Hexane was isomerized to branched products by contacting with trifluoromethanesulfonic acid in admixture with arsenic pentafluoride at 25°C for two hours. In the run 10.2 g (0.06 mole) of arsenic pentafluoride, 50 ml (85 g, 0.56 mole) trifluoromethanesulfonic acid, and 17.2 g (0.2 mole) of n-hexane were used. The results of the isomerization are given below in Table IV.

dimethylbutane than the use of trifluoromethanesulfonic acid alone.

I claim:

1. A process for the isomerization of paraffinic hydrocarbons which comprises contacting a feed comprising paraffinic hydrocarbons in a conversion zone at isomerization conditions with a catalyst consisting of trifluoromethanesulfonic acid.
2. A process according to claim 1 wherein the paraffinic hydrocarbon is normal hexane.
3. A process according to claim 1 wherein said feed comprises paraffinic hydrocarbons having from 4 to 7, inclusive, carbon atoms per molecule and said contacting is effected at a temperature in the range of 0-100°C

25

TABLE IV

Run	Hexane Conv. %	Selectivity to Cracked Products	Light Products (C ₃ ,C ₄ 's,C ₅ 's)	Heavies	2,2-DMB	DIP+2-MP	3-MP
6	97.0	74.1	59.2	14.9	13.9	9.1	2.8

It will be observed from the above run that the use of arsenic pentafluoride admixed with trifluoromethanesulfonic acid gives a higher selectivity to 2,2-

and a pressure sufficient to maintain the reactants and catalyst in the liquid phase.
